MASSAGE INSTRUMENT

Sheridan R. Ross and John Franklin Dare,
San Francisco, Calif.

Application October 13, 1941, Serial No. 414,824

2 Claims. (Cl. 128—60)

The present invention relates to massage instruments, and particularly to instruments for effecting massage or manipulation of the prostate gland and regions adjacent thereto.

It is the object of this invention to provide an instrument by means of which an individual may treat his own prostate gland by massage or manipulation thereof in a manner which approximates as closely as possible the treatment administered by a doctor.

A further object of the invention is the provision of an instrument which resembles the human finger in shape and action, and which may be inserted in the rectum or other body cavity and manipulated exteriorly to effect a massaging action interiorly of such cavity.

Further and more specific objects of the invention and advantages of its construction and use are made apparent in the following specification, wherein reference is made in detail to the accompanying drawing, in which one form of the invention is shown for purposes of illustration.

In the drawing—

Fig. 1 is a vertical sectional view of the massaging portion of the instrument of the present invention;

Fig. 2 is a similar view with the parts in a different position; and

Fig. 3 is a perspective view of the entire instrument.

As illustrated in Fig. 3, the instrument comprises a finger-like massaging member 10 supported on the lower end of a handle 11. Pivotable to the handle 11 by means of a pin 12 is a lever 13, manipulation of which causes the finger 10 to move to and from the positions illustrated in Figs. 1 and 2. A pin 14 in the handle 11 serves as a stop to limit the movement of the lever 13.

The construction of the finger 10 is best illustrated in Figs. 1 and 2, wherein the lower portion of the finger is shown as formed of a rigid hollow post 15, threaded to a socket 16 formed at the lower end of the handle. The upper end of the finger is formed of a tip 17 which is connected to the post 15 by a pair of links 18 and 19. The link 18 is pivoted to the tip 17 by means of a pin 20 and to the post 15 by means of a pin 21. The link 19 is pivoted to the tip 17 by a pin 22 and to the post 15 by a pin 23. A rod 24 is pivoted to the link 19 by a pin 25. The upper end of the rod 24 is bifurcated to receive the link 19 at the point where the pin 25 passes through it. The lower end of the rod 24 passes through the lower end of the lever 13 and is threaded to receive a nut 26. 55

The rod 24 is provided with a collar 27 adjacent its upper end, and is guided by a nut 28 which is centrally bored slidably to receive the rod, and which is threaded into the lower end of the collar 5 16. A spring 29 is interposed between the collar 27 and the nut 28, and, being compressed between these two members, normally tends to raise the rod 24 and to retain the links 18 and 19 and the tip 17 in a position aligning with the post 15, as 10 illustrated in Fig. 1.

Compression of the lever 13 toward the handle 11 swings the lower end of the lever downwardly, which draws the rod 24 downwardly against the tension of the spring 29, thus swinging the link 15 19 about its pivot 23 and causing the legs 18 and 19 and the tip 17 to assume the position illustrated in Fig. 2, which position is similar to that assumed during massaging action of the human finger. Upon release of the handle the spring 20 returns these members to their original position, so that a natural massaging action may be obtained by alternate compression and release of the handle 13.

The shape of the handle and lever 13 is such 25 that they have a short portion illustrated at 30 in Fig. 3, extending at right angles to the finger 10, and remaining portions sloping upwardly therefrom. Consequently the finger 10 may be 30 inserted in the rectum in a proper position for massage of the prostate gland, with the portion 30 extending forwardly between the legs and the portions of the handle and lever which are 35 grasped to manipulate the finger conveniently positioned for operation by the patient receiving the treatment.

The entire finger, including the post 15, the 40 levers 18, 19, and the tip 17, is preferably encased by a soft resilient material, such, for example, as 40 rubber, shown at 31, and this tube-like casing is preferably removable to enable the entire device to be thoroughly cleaned and sterilized. It is desirable, particularly where the device is being 45 used for treatment of the prostate gland, that the rubber be thickened toward the lower end of the finger-like member to provide a shoulder 32 to limit the distance to which the device may be inserted and thus insure the tip end being positioned in the region of the gland.

50 The spacing between the pivotal connections 20, 21, 22 and 23 is preferably such that, upon compression of the lever, the tip 17 is swung slightly beyond a line parallel to the post 15, as 55 illustrated in Fig. 2. The exact angle to which any of the sections are swung upon manipula-

tion of the lever may, however, be varied to effect the most desirable massaging action.

While the present invention is herein disclosed in a particular form, more or less specifically described, it is to be understood that this disclosure is for purposes of illustration and that various changes may be made in the construction and arrangement of the several parts shown, all within the scope of the appended claims.

Having thus described and illustrated my invention, what I claim and desire to secure by Letters Patent is:

1. A massaging instrument comprising a rigid tubular member, a pair of parallel links pivoted thereto, a tip pivoted to said links, a rod extending through said tubular member and pivoted to one of said links at a point to cause swinging of said links about their pivots when the rod is

reciprocated, and means for reciprocating said rod to cause angular movement of said links and tip relative to the tubular member.

2. A massaging instrument comprising a rigid tubular member, a pair of parallel links pivoted thereto, a tip pivoted to said links, a rod extending through said tubular member and pivoted to one of said links at a point to cause swinging movement of said links about their pivots when the rod is reciprocated, means for reciprocating said rod to cause angular movement of said links and tip relative to the tubular member, spring means normally holding said links and tip in alignment, and means for reciprocating said rod to effect such angular movement.
